(57) **CLAIM**

The ornamental design for a protective case for earphone, as shown and described.

DESCRIPTION

FIG. 1 is a perspective view of a protective case for earphone, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 shown in FIG. 1;
FIG. 10 is an enlarged view of portion 10 shown in FIG. 1;
and,

FIG. 11 is an enlarged view of portion 11 shown in FIG. 2.
The dash-dash broken lines in the drawings depict portions
of the protective case for earphone that form no part of the
claimed design. The dot-dash broken lines represent bound-
aries of the enlarged portions and form no part of the claimed
design.
